UNITED STATES PATENT OFFICE.

CHARLES C. POWERS, OF WILLIAMS, ARIZONA, ASSIGNOR OF ONE-THIRD TO JACK T. UTNIK AND ONE-THIRD TO LOUIS DE BOLD, BOTH OF WILLIAMS, ARIZONA.

ELECTROMAGNET.

1,231,193.

Specification of Letters Patent. Patented June 26, 1917.

Application filed September 8, 1916. Serial No. 119,110.

To all whom it may concern:

Be it known that I, CHARLES C. POWERS, residing at Williams, in the county of Coconino and State of Arizona, have invented 5 a new and Improved Electromagnet, of which the following is a specification.

My invention has for its object to provide an electro magnet of the solenoid type in which the core member is preferably in the 10 form of an annulus or wheel-like structure and, to this end, the coil is wound in a novel manner back and forth on a ring-like tubular bobbin having its inner periphery slit to produce a space through which the supporting arms of the core may be moved, the 15 core being designed to rotate around the axis of the magnet.

The invention provides means whereby a 20 rotatable movable core (either in one piece or in a number of separate sections) may be employed in place of the conventional rectilinearly movable core of the common type of solenoids.

In its more subordinate nature, the invention 25 includes those novel features of construction, combination and arrangement of parts, all of which will be first fully described and then be specifically pointed out in the appended claims, reference being had 30 to the accompanying drawing, in which:

Figure 1 is a detail perspective view of a portion of my electromagnet.

Fig. 2 is a plan view of the core wheel and showing the coil element in horizontal 35 section.

Fig. 3 is an enlarged horizontal section on the line 3-3 on Fig. 4.

Fig. 4 is a cross section on the line 4-4 on Fig. 2, and

Fig. 5 is a detail section on the line 5-5 on Fig. 2.

Fig. 6 is a side elevation of a plurality of magnet sets operating in connection with a single shaft.

Fig. 7 is a top plan view of the same.

Fig. 8 is a detail view of a rectilinearly movable core form of the invention.

In the drawing in which like numerals of reference designate like parts in all of the 50 figures, it will be observed that the coils are made (preferably) in section and successively energized by any suitable device of known construction that may be employed

to shift and reverse the current flow to the various coils in proper order to effect rotation or oscillation of the core as may be found desirable for the particular use to which the invention may be put.

In the drawings, 1 is the pivotal shaft on which the core wheel structure is mounted 60 for rotation. This structure comprises the core 2, formed preferably of a plurality of magnetic (iron) sections 2, separated by a non-magnetic gap 3, which may be of brass, to form a continuation of the circle of the 65 core and be suitably fastened to the iron to form an integral structure. The core annulus is supported on the spider arms 4 which are attached to the shaft 1.

5 is an annular bobbin of insulating material having an inner peripheral slit 6 through which the arms 4 project, the core 2 being located within the bobbin 5 and adapted for motion within the same around the axis of the shaft 1. The coils, of which 75 a suitable number is provided, are wound in a peculiar manner and constitute one of the essential features of the present invention. The wire for the coil is passed around the pins 9 and wound around the bobbin 5, 80 from the upper side of the slit 6 to the lower side, and is then passed around another pin 10 and carried back again around the bobbin to the upper side of the slit as at 8, the coil portion 8 being wound away from the bobbin while the coil portion 7 is wound on or in contact with the bobbin. This method of winding is carried out in the successive coils, the terminal ends 11 of which are carried to a convenient place for connection 90 with the energizing circuit.

As the coils are successively energized, the core will be drawn around in a circular path and caused to rotate. If the current is alternately reversed, an oscillating movement may be imparted to the coil.

One or more bobbins and cores may be employed with the core spiders mounted on the shaft 1, one set above the other, see Figs. 6 and 7, and in this construction the 100 coils of the several sets are staggered with relation to one another and alternate coil sets are energized together, so as to exert a continuous tongue or pull.

From the foregoing description taken in 105 connection with the accompanying drawing,

it is thought that the construction of the invention will be clear to those skilled in the art.

What I claim is:

- 5 1. In an electromagnet, a tubular bobbin having a slot, energizing coils wound back and forth on said bobbin from slot to slot, a core member movable in said bobbin and an arm carrying said core member and projecting through said slot and movable with relation to said coils. 40
- 10 2. In an electromagnet, an annular tubular bobbin having an annular slot, energizing coils wound back and forth on said bobbin from slot to slot, a core member movable in said bobbin and an arm carrying said core member and projecting through said slot and rotatable around an axis, said core member comprising a plurality of sections of magnetic material spaced apart. 45
- 15 3. In an electromagnet, an annular tubular bobbin having an annular slot, energizing coils wound back and forth on said bobbin from slot to slot, a core member movable in said bobbin and an arm carrying said core member and projecting through said slot and rotatable around an axis, said core member including a plurality of sections of alternately magnetic and non-magnetic material. 50
- 20 4. In an electromagnet, an annular tubular bobbin having an annular slot, energizing coils wound on said bobbin, a core member movable in said bobbin and an arm carrying said core member and projecting through said slot and rotatable around an axis, said core member comprising a plurality of sections of magnetic material, said coils being wound back and forth around said bobbin from slot to slot, alternate turns being wound close to the bobbin and the remaining turns spaced away from the bobbin. 55
- 25 5. In an electromagnet, an annular tubular bobbin having an annular slot, energizing coils wound on said bobbin, a core member movable in said bobbin and an arm carrying said core member and projecting through said slot and rotatable around an axis, said core member comprising a plurality of sections of magnetic material, said coils being wound back and forth around said bobbin from slot to slot, alternate turns being wound close to the bobbin and the remaining turns spaced away from the bobbin. 60
- 30 6. In an electromagnet, an annular tubular bobbin having an annular slot, energizing coils wound on said bobbin, a core member movable in said bobbin and an arm carrying said core member and projecting through said slot and rotatable around an axis, said core member including a plurality of sections of alternately magnetic and non-magnetic material, said coils being wound back and forth around said bobbin from slot to slot, alternate turns being wound close to the bobbin and the remaining turns spaced away from the bobbin. 65
- 35 7. In an electromagnet, an annular tubular bobbin having an annular slot, energizing coils wound on said bobbin, a core member movable in said bobbin and an arm

CHARLES C. POWERS.
